GINE CO., OF GRAND RAPIDS, WISCONSIN, A CORPORATION OF WISCONSIN.

PACKING FOR ROTARY ENGINES AND COMPRESSORS.

1,409,985.

Specification of Letters Patent. Patented Mar. 21, 1922.

Application filed December 29, 1919. Serial No. 347,897.

To all whom it may concern:

Be it known that we, HENRY S. WHITE, a subject of the King of Great Britain, and ALEXANDER B. BOYER, a citizen of the United States, residing at Chicago and Riverside, respectively, in the county of Cook and State of Illinois, have invented a certain new and useful Improvement in Packings for Rotary Engines and Compressors, of which the following is a specification.

Our invention relates to an improved form of packing for the rotary piston or inner element in a device of the class comprised of rotary engines, compressors and the like where the inner element which may be called a rotor or piston moves relatively to an enclosing casing under the action of fluid under pressure or for the purpose of compressing or pumping fluid and the like. By our invention we provide an improved means by which the outer surface of the rotor or inner member may be made fluid tight relatively to the inner surface of the casing and also means by which the end walls of the inner member may be made fluid tight relatively to the end walls of the casing.

In the present case we show a form of compressor merely as a means of illustrating the use of our improved packing devices, which compressor per se forms no part of our present invention and is not herein claimed; it will be understood that our packing is equally applicable to any device of the class illustrated by the compressor herein shown as long as said device functions by relative lateral movement of an inner member in an enclosing casing under conditions where two variable compartments are formed between the casing and the inner member which must be separated in a manner to preserve a difference of fluid pressure between them.

Our invention will best be understood by reference to the accompanying drawings showing a preferred embodiment thereof in which—

Fig. 1 shows a compressor in transverse sectional view to show the packing device in place on the inner member of said compressor,

Fig. 2 is a longitudinal sectional view

through the casing of the device shown in Fig. 1 and shows the inner element of the compressor in front elevation,

Fig. 3 is an enlarged sectional view taken longitudinally of the compressor through the lower part of the inner element and outer element to show the construction and location of the packing elements on the inner member of the compressor, this view being taken along the line 3—3 in Fig. 1, and

Fig. 4 shows in a view similar to Fig. 3 a modified construction of inner member permitting the use of part of our packing devices to accomplish the function intended of packing the ends of the inner member against the corresponding end walls of the construction.

Similar numerals refer to similar parts throughout the several views.

The construction of the compressor shown in the drawings, consists of a cylindrical casing having end walls 1 and a cylindrical shell 2 bored internally to engage the operating parts contained in the casing. The casing has projecting inwardly and radially from its outer wall a diaphragm 4 which is rigidly secured to the casing. A rotor 5 is disposed eccentrically in the casing and consists of a cylindrical member mounted on a suitable shaft 6. The rotor 5 is provided with a recess for receiving the diaphragm 4 and suitable guide plates 8 and 9 mounted on either side of the diaphragm supported upon bearing pins or rods 16, which construction permits a slight degree of angular motion of the diaphragm relatively to the rotor as the device is operated. The shaft 6 and the ends of the compressor are provided with suitable bearings not shown for supporting the parts to maintain the eccentric relation shown in Fig. 1 and in the particular construction of the device illustrated in the drawings both the casing and the rotor are arranged to rotate in the direction of the arrow by suitable means as a result of which the compartments 10 and 11 on either side of the diaphragm 4 are increased and decreased in size to draw in air through the port 18 and expel it through the port 20 and check valve 22. The port 18 communicates

with a bore 19 in one end of the shaft 6 and the chamber of the valve 22 at its inner end communicates by a passageway 23 with a bore 24 through the other end of the shaft 6, 5 the bores in the shaft being separated from each other.

The relation between the rotor and the casing is such that the rotor is practically in contact with or tangent to the inner cylindrical surface of the casing along the lower longitudinal element of the rotor, being separated therefrom slightly to prevent friction and wear.

To prevent leakage of air under pressure 15 we provide packing devices as follows: In each end of the rotor 5 we form edge grooves for receiving flat packing rings 12 of metal, resting against the inner surfaces of the ends of the casing, and within the 20 rings 12 said grooves are extended towards each other with relatively converging inclined faces to receive split metal contraction rings 13, similar in nature to piston rings ordinarily used in engine construction, 25 the differences being that said rings tend to contract instead of expand and that they are of triangular cross section instead of rectangular. The inner converging edge surfaces of the rings 13 closely fit the corresponding surfaces of the grooves provided 30 to receive them and the outer vertical edge surfaces of said rings 13 closely fit the inner vertical faces of the rings 12. As a result of this construction, the tendency of the 35 rings 13 to contract exerts an axial thrust upon the rings 12 forcing them outwardly to closely fit the inner surfaces of the ends of the casing. To prevent leakage from the compartment 11 to the compartment 10 40 through the tangent point between the compressor elements, we provide longitudinal grooves of T-shaped cross section in the cylindrical surface of the rotor 5 to receive baffle bars 14 of similar cross section, the 45 relation between the bars and slots being such that said bars are incapable of circumferential movement in said slots but may slide freely therein radially within limits to permit the bars when in their outermost position to have a radius somewhat greater 50 than the minimum distance between the axis of the motor and the inner cylindrical surface of the casing. This results in a plurality of said bars at all time engaging said 55 inner cylindrical surface at the point of tangency of said rotor with said surface. The inner surfaces of the bars 14 when said bars are passing said tangent point, are just clear of the outer surfaces of the rings 13, while 60 the rings 12 are continued outwards radially beyond the rings 13 so that their outer diameter is substantially the same as the diameter of the body of the rotor. The grooves for receiving the rings 13 are of substantially 65 the same size and shape as said rings, that

is to say said grooves do not extend outwards radially beyond said rings, and the T-shaped grooves referred to are continued of uniform cross section through the body of the rotor 5 and also through the rings 12. 70 The bars 14 are of substantially the same length as the dimension between the inner vertical faces of the casing, and we provide in each bar one or more radial holes 14^a so that the back faces of the bars will at all 75 times be subjected to the same unit fluid pressure as their outer faces are subjected to. The grooves for the rings 13 open into the grooves for the bars 14 and thus the outer faces of the rings 13 are subjected to 80 the same unit fluid pressure as are the inner faces of the bars 14. The initial tension on the rings 13 when placed in their grooves is sufficient to overcome the effect of the centrifugal force to be imparted to them and to 85 positively hold the rings 12 against the end surfaces of the casing to prevent leakage for low pressure in the compartment 11; when the pressure of the fluid in compartment 11 is increased the pressure is correspondingly 90 increased back of each bar 14 in said compartment and also on the outer face of each ring 13. For high pressure machines therefore, the initial tension in the rings 13 may be made very light, or even reduced to zero, 95 and each ring may consist of several sections, the better to provide for contraction, since an increase in pressure in compartment 11 and the consequent increase of pressure on the outer cylindrical faces of rings 13 100 provides the necessary tendency in the rings 13 to contract and to exert axial pressure on rings 12. The amount of this axial thrust is regulated by the degree of inclination of the inner edge faces of rings 13 and of the 105 faces of their supporting grooves. The bars 14 have the fluid pressure balanced on their inner and outer faces and by reason of the centrifugal force imparted to them in the rotation of the machine they are during the 110 operation of the machine continually held in their outer or packing position. As they approach the point of tangency of the inner and outer members their outer faces come into contact with the inner face of the outer 115 member or casing and when in this position the pressure of the fluid on their outer faces is wholly or partly relieved so that the fluid pressure on their inner faces will hold them firmly in contact with the said inner face 120 of said outer member. Thus the seal between rings 12 and the inner end walls of the outer casing member, the seal between rings 13 and rings 12, the seal between rings 13 and the grooves in the inner rotating 125 member, and the seal between the bars 14 and the inner circumferential surface of the outer rotating member all become more effective as the fluid pressure in compartment 130 increases.

Our construction therefore provides a means by which the pressure upon the packing varies in proportion to the requirements of different conditions of operation of the device, thus eliminating unnecessary packing pressure and its incident friction and wear when low fluid pressures are developed.

In certain cases, as for example where low pressures only are developed, the bars 14 and rings 12 may be dispensed with and a construction as shown in Fig. 4 may be employed. In this case grooves of triangular cross section are formed in the outer edges of the end faces of the rotor 5^a to receive the rings 13 which bear directly against the inner surfaces of the ends of the casing. In other respects the construction may be the same as above described. In this case as before, the pressure of the rings against the 20 ends of the casing will vary with the fluid pressure developed in the device.

Our packing is susceptible of a wide variety of applications whether for compressors, pumps or prime movers, in fact for 25 any kind of apparatus requiring packing of the class herein described.

While we have shown our invention in the particular embodiment above described, it will be understood that we do not limit ourselves to this exact construction as we may employ equivalents known to the art at the time of the filing of this application without departing from the scope of the appended claims.

35. What we claim is:

1. An end packing for a cylindrical member comprising a packing ring carried by the end of said member, and a contraction ring carried by said member and engaging said 40 packing ring to produce axial pressure on said packing ring by the inwardly directed radial pressure of said contraction ring.

2. An end packing for a cylindrical member comprising a flat metal packing ring carried by the end of said member, and a triangular metal contraction ring carried by said member and engaging said packing ring to produce axial pressure on said packing ring by the inwardly directed radial pressure 50 of said contraction ring.

3. An end packing for a cylindrical member comprising a packing ring carried by the end of said member, and a contraction ring carried by said member and engaging said packing ring to produce axial pressure on said packing ring by the inwardly directed radial pressure of said contraction ring, said contraction ring forming a fluid tight fit with said member and said packing 55 ring.

4. An end packing for a cylindrical member comprising a flat metal packing ring carried by the end of said member, and a triangular metal contraction ring carried by 60 said member and engaging said packing ring

to produce axial pressure on said packing ring by the inwardly directed radial pressure of said contraction ring, said contraction ring forming a fluid tight fit with said member and said packing ring.

5. An end packing for a cylindrical member comprising a packing ring carried by the end of said member, and a contraction ring carried by said member and engaging said packing ring to produce axial pressure on 70 said packing ring by the inwardly directed radial pressure of said contraction ring, and said contraction ring forming a fluid tight fit with said member and said packing ring, said contracting ring being subjected to the fluid pressure of the device, whereby said inwardly directed radial pressure varies with said fluid pressure.

6. An end packing for a cylindrical member comprising a flat metal packing ring 85 carried by the end of said member, and a triangular metal contraction ring carried by said member and engaging said packing ring to produce axial pressure on said packing ring by the inwardly directed radial pressure 90 of said contraction ring, said contraction ring forming a fluid tight fit with said member and said packing ring, said contracting ring being subjected to the fluid pressure of the device, whereby said inwardly directed radial pressure varies with said fluid pressure.

7. An end packing for a cylindrical member comprising a flat metal packing ring carried by the end of said member, and a triangular metal contraction ring carried by said member and engaging said packing ring to produce axial pressure on said packing ring by the inwardly directed radial pressure of said contraction ring, the triangular 100 section of said contraction ring having its base outermost and an inclined face for engaging said member.

8. A packing for a cylindrical member comprising an end packing ring, longitudinal baffle bars of uniform cross section extending through corresponding slots in said ring, and a contraction ring inside of said bars between said packing ring and said member for producing an outward axial 115 thrust on said packing ring by contraction of said contraction ring.

9. A packing for a cylindrical member comprising an end packing ring, longitudinal baffle bars of uniform cross section extending through corresponding slots in said ring, and a contraction ring inside of said bars between said packing ring and said member for producing an outward axial thrust on said packing ring by contraction 120 of said contraction ring, said bars having apertures producing equal unit fluid pressure on the outer and inner surfaces of said bars and on the outer surface of said contraction ring.

10. An end packing for a cylindrical member having a circular end groove comprising a metal contraction ring for placement in said groove and having a cross section producing axial movement of said ring upon radial contraction thereof.
11. An end packing for a cylindrical member having a circular end recess having an inclined edge face and of increasing width outwardly comprising a split metal contraction ring having outwardly diverging edge faces to fit the inclined edge face of said recess and the casing containing said member.
12. An end packing for a cylindrical member having a circular end recess comprising a metal packing ring and a split metal contraction ring for placement in said recess, said split ring being restrained when in place and tending to decrease its radial dimensions, said rings having cooperating cross sections producing outward axial movement of said packing ring upon a decrease in the radial dimensions of said split ring.
13. A packing for a device having a hollow casing with substantially parallel inner end surfaces and an inner member having substantially parallel end walls adjacent said inner end surfaces and adapted to movement laterally in said casing comprising end packing rings of metal to be carried by said member to engage said inner surfaces and split metal contraction rings to be carried by said member between it and said packing rings, said split rings being restrained radially when in place and tending to contract radially to move said packing rings apart.
14. A packing for a device having a hollow casing with substantially parallel inner end surfaces and an inner member having substantially parallel end walls adjacent said inner end surfaces and adapted to movement laterally in said casing comprising end packing rings of metal to be carried by said member to engage said inner surfaces and split triangular metal contraction rings with their bases outermost to be carried by said member between it and said packing rings, said split rings being restrained radially when in place and tending to contract radially to move said packing rings apart.
15. A packing for a device having a hollow casing with substantially parallel inner end surfaces and an inner member having substantially parallel end walls adjacent said inner end surfaces and adapted to movement laterally in said casing and having end grooves with outwardly converging end walls comprising flat end packing rings of metal and split metal rings engaging said packing rings and having inner outwardly converging edge surfaces, said split rings being restrained radially when in place and tending to move inwardly and apart.
16. A packing for a device having a hollow cylindrical casing with substantially parallel inner end surfaces and an inner member having substantially parallel end walls adjacent said inner end surfaces and adapted to movement laterally in said casing and having longitudinal grooves in its cylindrical surface and end grooves comprising baffle bars fitting said longitudinal grooves circumferentially and having limited motion therein radially, metal packing rings and split metal contraction rings for placement in said end grooves, said bars being of uniform cross section through corresponding slots in said packing rings and said split rings engaging said packing rings and said end grooves within said bars and having inclined edge faces and restrained when in place and tending to move inwardly to move said packing rings apart.
17. A packing for a device having a hollow cylindrical casing with substantially parallel inner end surfaces and an inner cylindrical member having substantially parallel end walls adjacent said inner end surfaces and adapted to movement laterally in said casing and having longitudinal grooves in its cylindrical surface and end grooves comprising baffle bars fitting said longitudinal grooves circumferentially and having limited motion therein radially, metal packing rings and split metal contraction rings for placement in said end grooves, said bars being of uniform cross section through corresponding slots in said packing rings and said split rings engaging said packing rings and said end grooves within said bars and having inclined edge faces and restrained when in place and tending to move inwardly to move said packing rings apart.
18. A packing for a device having a hollow cylindrical casing with substantially parallel inner end surfaces and an inner cylindrical member having substantially parallel end walls adjacent said inner end surfaces and adapted to movement laterally in said casing and having longitudinal grooves in its cylindrical surface and end grooves having outwardly converging edge surfaces comprising baffle bars of uniform T-shaped cross section, flat metal packing rings and split metal contraction rings for placement in said end grooves in engagement with each other, said packing rings having slots receiving the ends of said bars and said split rings being within said bars, said bars fitting said longitudinal grooves and said slots circumferentially and having limited movement therein radially, said split rings having outwardly converging inner edge surfaces for engaging the corresponding edge surfaces of said end grooves and

tending when in place to move inwards radially and from each other to move said packing rings apart.

19. A packing for a device having a hollow cylindrical casing with substantially parallel inner end surfaces and an inner cylindrical member having substantially parallel end walls adjacent said inner end surfaces and adapted to movement laterally in said casing and having longitudinal grooves in its cylindrical surface and end grooves having outwardly converging edge surfaces comprising baffle bars of uniform T-shaped cross section, flat metal packing rings and split metal contraction rings for placement in said end grooves in engagement with each other, said packing rings having slots receiving the ends of said bars and said split rings being within said bars,

said bars fitting said longitudinal grooves 20 and said slots circumferentially and having limited movement therein radially, said split rings having outwardly converging inner edge surfaces for engaging the corresponding edge surfaces of said end grooves and 25 tending when in place to move inwards radially and from each other to move said packing rings apart, said bars having apertures through them to produce equal unit fluid pressure on the outer and inner surfaces 30 of said bars and on the outer circumferential surfaces of said split rings.

In witness whereof, we hereunto subscribe our names this 20th day of December, A. D. 1919.

HENRY S. WHITE.
ALEXANDER B. BOYER.
